EDWARD H. LANGE, OF NEW YORK, N. Y.

METHOD AND MEANS FOR STABILIZING AMPLIFIERS.

Application filed August 28, 1925. Serial No. 33,002.

This invention relates to thermionic amplifiers and has particular reference to means for amplifying radio frequency signals in a multi-stage thermionic amplifier without troublesome regeneration normally encountered in the individual stages due to unavoidable capacity between the electrodes of the thermionic tubes. In multi-stage untuned radio frequency amplifiers, unbalanced magnetic or capacitive coupling between input and output circuits of the separate stages results in lack of independence of tuning of the separate stages, which is detrimental to the uniformity and duplication of condenser settings for a particular signal frequency, and results also in poor quality reproduction of the received signal.

The object of this invention is to provide simple method and means whereby inherent and extraneous capacitive coupling between grid and plate of the thermionic tubes of the separate stages of a multi-stage amplifier can be exactly balanced over a range of frequencies, and energy transfer from the output to the input elements of the separate stages prevented. In a multi-stage thermionic amplifier, coupling normally exists between the input and output elements of the separate stages, which is either magnetic or capacitive or both. By means of this coupling energy is fed back from the output elements to the input elements, which gives rise to increased amplification, but introduces irregularities in the tuning of the similar separate stages, which independently tune at the same settings. When the energy fed back due to mutual reactance between the input and output elements of the thermionic tube is sufficient to overcome the circuit losses, self sustained oscillations are produced within the amplifier which interfere with the amplified impressed signal. The magnetic coupling between input and output elements of the individual stages can be eliminated by proper shielding of the magnetic elements of the circuit, or by proper orientation of the magnetic elements. The present invention deals with a method for annulling the electromotive forces impressed upon the input circuits of the separate stages from the respective output circuits due to inherent and extraneous capacity which exists between the input and output elements of the thermionic tubes of the separate stages.

Referring to the accompanying drawings;

Fig. 1 shows diagrammatically a four stage amplifier and detector with an embodiment of my invention applied thereto.

Fig. 2 illustrates in diagram form the method of stabilizing the amplifier shown in Fig. 1.

Referring in particular to Fig. 1 a direct coupled tuned radio frequency amplifier having four tuned stages and a detector is shown. Grid 5 of the first stage is energized by means of the antenna 1, and coupled circuit 2, 3, or directly by the tuned circuit 2, 3, alone. The output impedance of the first tube consists of a tuned circuit 8, 9, in series with a condenser 7. The capacity of the condenser 7, is sufficiently large to make the voltage drop across 7, small compared with the drop across the tuned circuit 8, 9. The condenser 7, serves to keep the steady plate potential from the grid 11, the alternating component of plate current being confined to the output circuit 6, 7, 8, 9, 4, by means of the radio frequency choke coil 13, through which the steady plate current is supplied from the source 26. The choke coils 18, 19 and 21, perform a similar function to choke coil 13, and the condensers 17, 23, and 24, perform a function similar to condenser 7. Due to the inter-electrode capacity 5, 6, the input circuit 2, 3, is not independent of the output circuit 6, 7, 8, 9, 4, but together with the capacity 5, 6, in series, the input circuit 2, 3, is shunted across the output circuit. Normally, when the circuits 2, 3, and 8, 9, are very nearly in tune for a certain frequency, the resultant reactance of each of these circuits is inductive, and relatively large compared with the reactance of the individual inductance coils alone, and the voltage drop across 2, 3, due to its shunt connection across the output inductive reactance 7, 8, 9, through the relatively high capacity reactance 5, 6, is in proper phase to reinforce the current in the output circuit. This process gives rise to regeneration, or to self sustained oscillations if sufficient energy is fed back from the output to the input circuit to overcome the circuit losses. In the direct coupling used between the stages or in other forms of coupling between the output circuit of any tube and the input circuit of the following tube, a phase reversal is obtained between the output circuits of successive tubes. The alternating voltage drop across 16, 15, is substantially 180° out of phase with the drop across 8, 9, and

larger than the drop across 8, 9, in proportion to the resultant amplification of the intervening tube. By means of the connection 14, a voltage drop across 14, 15, is obtained which is substantially equal in magnitude and opposite in phase to the drop across 8, 9. The voltage across 14, 15, is applied to the grid 5, by means of a stabilizing condenser 12, thereby reducing the voltage 10 across 2, 3, due to reaction of the output circuit 6, 7, 8, 9, 4, to zero. The stabilizing condensers 20 and 22, perform a function similar to condenser 12.

The balancing circuit can be better understood by reference to Fig. 2. The voltage drops across the circuits 7, 8, 9, and 14, 15, are represented by synchronous alternators having equal and opposite electromotive force, and connected to the common point 4, 20 which is the common filament connection of the tubes in Fig. 1. The interelectrode capacity 5, 6, and stabilizing capacity 12, form a closed circuit across the terminals 6, 14. By proper adjustment of the stabilizing condenser 12, the voltage across 5, 4, due to the combined action of the two alternators can be reduced to zero. The numerals in Fig. 2, correspond to the same circuit points in Fig. 1.

30 In Fig. 1, the anode circuits are energized from a common battery source 26, and the cathodes from the common battery source 25, but the method of stabilizing herein described is not restricted to this method of energy supply. Manifestly energy may be drawn from any other suitable source such as a battery eliminator or the like. In similar manner it will be understood that many other changes and modifications in the specific embodiment shown may be made within the scope of my invention and the spirit of the appended claims.

What I claim is:

1. The method of preventing regeneration in a conductively coupled amplifier provided with a plurality of subsidiary amplifying means having, tuned input circuits, tuned output circuits, and inherent capacity between said circuits, which comprises inserting capacitance between the input circuit of one said means and the output circuit of another said means and thereby impressing upon the first said input circuit electromotive force substantially equal and opposite to that impressed upon said input circuit from the output circuit of said first means through said inherent capacity.

2. The method of preventing regeneration in a conductively coupled amplifier embodying a series of amplifying means each having a tuned input circuit, a tuned output circuit, and inherent capacity between said circuits, which comprises inserting capacitance between said input circuit of one said means and the output circuit of the succeed-

ing said means, and through the medium of said capacitance impressing upon the first said means input circuit an electromotive force component opposing that impressed upon said first means input circuit from the 70 first means output circuit.

3. In a thermionic amplifier having a plurality of stages each provided with a tuned input circuit, a tuned output circuit, inherent capacity between said circuits, a continuous 75 current anode energizing circuit containing a choke coil; and a conductive connection from said stage output circuit to the succeeding stage input circuit; a condenser separating said anode energizing circuit and said 80 succeeding stage input circuit, said condenser preventing said continuous current from the anode energizing circuit flowing to said succeeding stage input circuit, and a stabilizing condenser connected from the 85 first said stage input circuit to a point in said succeeding stage tuned output circuit, whereby an electromotive force of substantially equal magnitude and opposite phase to that applied to the first said stage input 90 circuit through said inherent capacity from said output circuit of said first stage is applied to said input circuit.

4. In a stabilizer for thermionic amplifiers having a plurality of stages each including 95 a tube having a cathode, anode, control electrode, inherent capacity between electrodes, a conductive coupling between the tuned output circuit of one said stage and the following stage control electrode, and an anode 100 energizing circuit containing a high impedance choke coil; a condenser connected between each anode and the tuned output circuit of the same stage, said condenser serving to prevent the flow of continuous current from said anode to the control electrode of the following stage, and a stabilizing condenser connected between the control electrode of one stage and a point in the following stage tuned output circuit, said stabilizing condenser serving to impress upon the control electrode a reactive voltage drop of opposite phase to the voltage impressed upon said control electrode from the anode 115 of the same stage by reason of said inherent capacity.

5. The combination in a thermionic multi-stage amplifier each of whose stages include a cathode, anode, control electrode, inherent capacity between electrodes, and a continuous current anode energizing circuit including a choke coil, a single tuned circuit between said stages and common to the output circuit of one stage and the input circuit of the following stage, a separating condenser connected between each stage anode and the said tuned output circuit of the same stage, said condenser preventing flow of continuous current from said anode to the following stage control electrode, and a sta- 120 125 130

bilizing circuit including a stabilizing condenser connected from the control electrode of one stage to an intermediate point on the inductive portion of the tuned output circuit of the following stage, said stabilizing circuit providing balancing means whereby the voltage drop across said inductive portion obtained by amplification in the intervening stage is balanced against the voltage drop impressed upon the control electrode from the output circuit of the same stage. Signed at New York, in the county of New York and State of New York, this 27th day of August, 1925.

EDWARD H. LANGE.
